UNITED STATES PATENT OFFICE.

CLEMENS TITTEL, OF GRATWEIN, AUSTRIA-HUNGARY.

APPARATUS FOR SMOOTHING THE PAPER WEB IN PAPER-MAKING MACHINES.

No. 828,149.

Specification of Letters Patent.

Patented Aug. 7, 1906.

Application filed February 14, 1906. Serial No. 301,079.

To all whom it may concern:

Be it known that I, CLEMENS TITTEL, a subject of the German Emperor, residing at Gratwein, near Graz, Styria, Austria-Hungary, have invented certain new and useful Improvements in Apparatus for Smoothing the Paper Web in Paper-Making Machines, of which the following is a specification.

As is known, in paper-making machines the paper web comes from the last wet-press with a perfectly-closed surface; but on passing the first drying-cylinder it has already lost this closed surface, because the closed pores are opened again by the evaporated moisture. The paper consequently becomes rough, which is detrimental to many printing operations. It has hitherto been endeavored to obviate this disadvantage by the provision of the so-called "damp-smoothing" apparatus in front of the last drying apparatus; but as the paper is already too dry at this part of the machine the pores only close very imperfectly, and the paper receives a "slaty" surface.

The present invention relates to apparatus whereby the opening of the pores during the passage of the paper web through the entire drying apparatus is prevented, all roughness being done away with as soon as it is produced.

This apparatus consists, mainly, in the provision of two or more chilled cast-iron rollers brightly polished or provided with a bright coating of copper or bronze, which are arranged behind each drying-cylinder of the first group. The paper web is led between these pairs of rollers, which may be heated, if required, and which are pressed against each other by screw-spindles.

This smoothing apparatus for smoothing the paper web, which is independent of the

drying-cylinders, can be arranged separately behind each drying-cylinder of the first cylinder group.

The accompanying drawing shows the arrangement of three such smoothing apparatus P' P^2 P^3 above the first three drying-cylinders of a paper-making machine.

These smoothing apparatus consist of two or more chilled-cast-iron rollers O and U , brightly polished or provided with a bright coating of copper or bronze, which may be heated, these rollers having their journals mounted in cast-iron frames S . The upper rollers O are adjustable by means of screw-spindles p and hand-wheels h for regulating the degree of smoothing. Each of the lower rollers carries a toothed wheel and receives a prescribed motion from the driving-wheel z , gearing therewith, and the conical belt-pulley k .

The paper web b before passing into the smoothing apparatus is led over a stretching-roller d , the bearings l of which are adjustable both in the horizontal and the vertical direction and whose object is to prevent creases on the paper entering the apparatus.

I claim—

In an apparatus of the class set forth, the combination of a drying-cylinder and heated smoothing-rollers having brightly-polished surfaces held in contact with each other, the rollers being disposed behind the drying-cylinder.

In testimony whereof I have hereunto set my hand in presence of two subscribing witnesses.

CLEMENS TITTEL.
